UNITED STATES PATENT OFFICE.

SAMUEL E. OVERTON, OF SOUTH HAVEN, MICHIGAN.

DESIGN FOR A CORNER-POST FOR CABINETS AND OTHER FURNITURE.

50,425.

Specification for Design.

Patented Mar. 6, 1917.

Application filed November 27, 1916. Serial No. 133,801. Term of patent 7 years.

To all whom it may concern:

Be it known that I, SAMUEL E. OVERTON, a citizen of the United States, residing at the city of South Haven, county of Van Buren, State of Michigan, have invented a new, original, and ornamental Design for Corner-Posts for Cabinets and other Furniture, of which the following is a specification, reference being had to the accompanying drawing, forming a part thereof.

Figure I is a front elevation view of a corner post showing my new design, and Fig. II is a side elevation view of the same.

I claim:

The ornamental design for a corner post for cabinets and other furniture, as shown.

SAMUEL E. OVERTON.

Witnesses:

E. R. EMMETT,
M. C. STURVY.
